CLAIM

The ornamental design for a hair brush barrel, as shown.

DESCRIPTION

FIG. 1 is a front perspective view of a hair brush barrel showing my new design.
FIG. 2 is a rear perspective view of my design of FIG. 1.
FIG. 3 is a side view of my design of FIG. 1.
FIG. 4 is a top view of my design of FIG. 1.
FIG. 5 is another side view of my design of FIG. 1.
FIG. 6 is a bottom view of my design of FIG. 1.
FIG. 7 is a front perspective view of a second version of my hair brush barrel design.
FIG. 8 is a rear perspective view of my design of FIG. 7.
FIG. 9 is a side view of my design of FIG. 7.
FIG. 10 is a top view of my design of FIG. 7.
FIG. 11 is another side view of my design of FIG. 7.
FIG. 12 is a bottom view of my design of FIG. 7.
FIG. 13 is a front perspective view of a third version of my hair brush barrel design.
FIG. 14 is a rear perspective view of my design of FIG. 13.
FIG. 15 is a side view of my design of FIG. 13.
FIG. 16 is a top view of my design of FIG. 13.
FIG. 17 is another side view of my design of FIG. 13.
FIG. 18 is a bottom view of my design of FIG. 13.
FIG. 19 is a front perspective view of a fourth version of my hair brush barrel design.
FIG. 20 is a rear perspective view of my design of FIG. 19.
FIG. 21 is a side view of my design of FIG. 19.
FIG. 22 is a top view of my design of FIG. 19.
FIG. 23 is another side view of my design of FIG. 19.
FIG. 24 is a bottom view of my design of FIG. 19.
FIG. 25 is a front perspective view of a fifth version of my hair brush barrel design.
FIG. 26 is a rear perspective view of my design of FIG. 25.
FIG. 27 is a side view of my design of FIG. 25.
FIG. 28 is a top view of my design of FIG. 25.
FIG. 29 is another side view of my design of FIG. 25; and,
FIG. 30 is a bottom view of my design of FIG. 25.
The broken lines in the drawings depict features that form no part of the claimed design.
